UNITED STATES PATENT OFFICE.

EDWIN J. ARMSTRONG, OF ERIE, PENNSYLVANIA, ASSIGNOR TO BALL ENGINE COMPANY, OF ERIE, PENNSYLVANIA, A CORPORATION OF PENNSYLVANIA.

POWER-SHOVEL.

1,163,633.

Specification of Letters Patent. Patented Dec. 14, 1915.

Application filed July 23, 1914. Serial No. 852,572.

To all whom it may concern:

Be it known that I, EDWIN J. ARMSTRONG, a citizen of the United States, residing at Erie, in the county of Erie and State of Pennsylvania, have invented new and useful Improvements in Power-Shovels, of which the following is a specification.

This invention relates to power shovels and consists in certain improvements in the construction thereof as will be hereinafter fully described and pointed out in the claims.

In the use of power shovels especially those used for grading and similar purposes where it is desired to level the surface from which the excavation has been made to grade it is advantageous to have means whereby the path of the cutting edge of the dipper may be so controlled as to give to the finished grade the uniform surface desired. It is also desirable that while the path of the dipper be limited in one direction so as to form this desired surface that the dipper be subject to manual control above this line so that it can be immediately lifted should it meet obstructions or for other purposes. It is further desirable that the limit of the path of the dipper be capable of variation so that the resultant surface left by the excavation may be level or slightly arched, as for instance the slope of an ordinary street.

The object of the present invention is to accomplish these results.

Details of construction forming further objects of the invention will appear from the specification and claims.

The invention is illustrated in the accompanying drawings as follows:

Figure 1 shows a side elevation of the front end of the power shovel. Fig. 2 a diagram showing the position of the lip of the dipper, dipper stick and controlling mechanism at different positions.

1 marks the shovel carriage, 2 the turntable, 3 the boom and 4 the stay for the boom. These are of ordinary construction. The dipper stick 5 is slidingly mounted in a yoke 6 (see dotted lines) in the usual manner. It has the rack 7 meshing with a gear 8. The gear 8 is fixed on a shaft 9 carried by a bearing 10. The dipper 11 having a cutting lip 11^a is carried by the dipper stick. A pulley block 12 is secured to the dipper and the cable 13 extends through the pulley block and over a pulley 14 at the upper end

of the boom and back to the hoisting mechanism (not shown) ordinarily carried by the turntable. A gear 15 is fixed on the shaft 9 and meshes with a gear 16. The gear 16 is driven by the engine 17. The engine is controlled through a controlling stem 18 operating on the usual valve (not shown) of the engine. These parts are of the usual construction. A bracket 19 is mounted on the engine and the controlling lever 20 is pivotally connected at 21 with the controlling stem 18. The lever 20 is pivoted at 22 on the bracket 19. The lever 20 is connected by a link 23 with an operating lever 24. The control of the dipper stick through the action of the operating lever 24 is one of common practice, that is to say, by handling the lever 24, the engine 17 may be driven ahead or reversed so as to elevate or depress the dipper stick through the connecting gears, the gear 8 operating on the rack 7.

The difficulty in handling one of these shovels where grading is desired to be done by the shovel arises from the fact that the swing of the dipper under the influence of the cable 13 is in an arc of a circle with the center of the shaft 9 as a center unless the dipper stick is synchronously moved by means of the engine 17. With a manual operation, it is very difficult, if not impossible, for an operator to so control the speed of the engine as to give to the lip 11^a of the dipper a path of travel along a pre-determined line so as to finish a grade as desired. To accomplish this automatically, I provide the following mechanism:—An extension 25 is arranged on the lever 20 and connected with a link 26 by means of a pin 27. The link 26 has a roller 29 which extends over a cam surface 28 on a lever 30. The lever 30 is pivotally mounted by means of a pin 31 on an arm 32 of a rock lever, the rock lever being mounted by means of a pin 33 on the bracket 19. The opposite arm 34 of the rock lever is connected by a pin 35 with a link 36 and the link 36 is pivotally connected with the dipper stick by a pin 37.

The link 36 has an extension 37^a and this extension is connected to a link 38 by means of a pin 39. The link 38 extends to the cam lever 30 and is connected with the cam lever 30 by means of a pin 40. The link 26 is held in position laterally by a link 41 which is connected to a lever 42. The operation of 110

this part of the device is as follows: Starting with the dipper in the position shown in Fig. 1, the operator holding the lever 24, the hoisting apparatus acting on the cable 13 is 5 started and the dipper stick starts on its outward travel. If the lever 24 was maintained in a fixed position or its control was neutral the dipper stick would swing in the arc of a circle with the axis of the shaft 9 as a center. 10 The operator exerts pressure on the operating lever 24 in forward direction and this maintains the roll 29 in contact with the cam surface 28 of the cam lever 30. The shape of the cam and its connection through the levers 32—34 and link 36 through the link 38 is such as to bring the control to neutral with the roller 29 on the cam surface 28 only 15 with the lip 11^a of the dipper in a pre-determined line, this line being the line at which it is desired to grade. The reason for this 20 operation is comparatively simple. With the controlling stem 18 in any other position than neutral steam will be on the engine to drive it either forward or backward in the ordinary well known manner. The engine 25 will only stop when this controlling stem has been brought to neutral position. By making a line which represents the desired grade from the point 11^a and then placing 30 this point at different points along this line, the cam 28 will be given various positions at each point. It is only necessary to shape this cam 28 so that at each point the roll 29 when resting on the cam will bring the controlling stem 18 to neutral. If, therefore, 35 the point 11^a on the dipper stick is above or below the pre-determined line at any given point in its outward travel this will result in a positioning of the cam 28 below or above 40 the point at which it will locate the roll 29 to bring the controlling stem 18 to neutral. If the cam 28 is above this point then the controlling stem 18 and the hand lever 24 will be forced to the left, and the engine will 45 be turned to lift the dipper. As the dipper is lifted, however, it rocks the arm 24 lowering the cam 28. The operator exerting pressure on the lever 24 follows this lowering movement and this continues until the 50 controlling stem 18 is brought to neutral and when it arrives at this position the engine stops. If the cam 28 is below the neutral position this will permit of a movement of 55 the lever 24 to the right under the pressure of the operator and this will result in a lowering of the dipper until the cam 28 has been lifted sufficiently to bring the stem 18 to neutral. It will be understood that in the normal operation of the engine, however, 60 there is not a successive sequence of movements. The engine moves slowly or fast so as to maintain the cam 28 approximately at the neutral point. The slightest variation from this starts the engine one way or the 65 other and thus the point 11^a is maintained in

practically the pre-determined line, and this is accomplished without jar or shock, the steam of the engine forming at all times a cushion. For instance when the operator lowers the shovel to take a fresh cut he forces the lever 24 forward bringing the shovel down at top speed and the shovel is checked when it reaches the desired line with no further care on the part of the operator. This checking is accomplished with the steam cushion of the engine, that is to say, any tendency of the dipper to go below the pre-determined line will put steam on the engine in a direction to lift the dipper so that the further movement of the dipper would be against the engine. This automatic catching of the dipper at a pre-determined point increases very materially the speed at which the shovel may be operated. In this way the lip of the dipper can be made to follow exactly the grade desired. At the same time, the operator has it in his power at any time to throw the lever 24 backward so as to lift the dipper. Thus, he can avoid obstructions such as large stones, or he can lift the dipper at any point in its travel where it is filled.

Fig. 2 shows diagrammatically the position of the links and the controlling pins together with the cam surface 28 in different positions in the travel of the dipper. It will be observed that the cutting lip 11^a describes a line X. In this diagram the dipper stick and controlling connections are shown in three different positions, the one in ordinary lines being that of Fig. 1 and the different pins and parts are given the same reference numerals. In the second position, the parts are shown in dash lines and the pins forming the connections are designated by the same numerals with the prime. In the third position, the parts are shown in double lines and the pins are designated by the same numerals with the exponent or index two. It will be noted that the roller 29 with each position of the cam surface is at neutral, that is, the position shown in Fig. 1 with the cutting lip of the shovel on the line X. It is sometimes desirable to change the predetermined line at X so as to give to the grade a pitch or slope as in grading a street. This may be accomplished in the present device by shifting the link 26 so as to shift the position of the roll 29. When this is done, the lever 20 is brought to neutral position only with a position of the lip 11^a along the predetermined line having a slight pitch. The lever 42 is, therefore, adjustable. It has a lip 43 which engages notches 44 in a segment 45. By shifting the lever 42, the predetermined line which will bring the controlling mechanism to neutral is shifted.

What I claim as new is:—

1. In a power shovel, the combination of

a boom; a dipper having a cutting lip; a dipper stick on which the dipper is mounted, said stick having a sliding and pivotal connection with the boom; mechanism for 5 swinging the stick on the pivotal connection; mechanism for actuating the dipper stick in the sliding connection to effect a sliding movement of the stick synchronously with the swinging movement; a motor actuating one of said mechanisms; and means 10 controlling said motor and controlled by the movement of the other mechanism to automatically limit the dipper lip to a predetermined line involving a synchronous pivotal and sliding movement of the dipper stick. 15

2. In a power shovel, the combination of a boom; a dipper having a cutting lip; a dipper stick on which the dipper is mounted, 20 said stick having a sliding and pivotal connection with the boom; mechanism for swinging the stick on the pivotal connection; mechanism for actuating the dipper stick in the sliding connection to effect a 25 sliding movement of the stick synchronously with the swinging movement; a motor actuating one of said mechanisms; and means controlling said motor and controlled by the movement of the other mechanism to automatically limit the dipper lip to a predetermined 30 line involving a synchronous pivotal and sliding movement of the dipper stick. 35

3. In a power shovel, the combination of a boom; a dipper having a cutting lip; a dipper stick on which the dipper is mounted, 40 said stick having a sliding and pivotal connection with the boom; mechanism for swinging the stick on the pivotal connection; mechanism for actuating the dipper stick in the sliding connection to effect a 45 sliding movement of the stick synchronously with the swinging movement; a motor actuating one of said mechanisms; means controlling said motor and controlled by the movement of the other mechanism to automatically limit the dipper lip to a predetermined 50 line involving a synchronous pivotal and sliding movement of the dipper stick; and apparatus for varying and controlling the means to vary the line through 55 which the dipper lip moves.

4. In a power shovel, the combination of a boom; a dipper having a cutting lip; a dipper stick on which the dipper is mounted, 60 said stick having a sliding and pivotal connection with the boom; mechanism for swinging the stick on the pivotal connection; mechanism for actuating the dipper stick in the sliding connection to effect a 65 sliding movement of the stick synchronously with the swinging movement; a motor actuating one of said mechanisms; means controlling said motor and controlled by the movement of the dipper stick under the influence of the other mechanism to automatically limit the dipper lip to a predetermined 70 line involving a synchronous pivotal and sliding movement of the dipper stick; and apparatus for varying and controlling the means to vary the line through 75 which the dipper lip moves.

tuating one of said mechanisms; means controlling said motor and controlled by the movement of the other mechanism to automatically limit the dipper lip to a predetermined line involving a synchronous pivotal and sliding movement of the dipper stick, 70 said means being free for manual operation to move the dipper stick in one direction to control the dipper stick at points above said line; and apparatus for varying and controlling the means to vary the line through which the dipper lip moves.

5. In a power shovel, the combination of a boom, a dipper having a cutting lip; a dipper stick on which the dipper is mounted, 80 said stick having a sliding and pivotal connection with the boom; mechanism for swinging the stick on the pivotal connection; mechanism for actuating the dipper stick in the sliding connection to effect a 85 sliding movement of the stick synchronously with the swinging movement; a motor actuating one of said mechanisms; and means controlling said motor and controlled by the movement of the dipper stick under the influence of the other mechanism to automatically limit the dipper lip to a predetermined line involving a synchronous pivotal and sliding movement of the dipper stick. 90

6. In a power shovel, the combination of a boom; a dipper having a cutting lip; a dipper stick on which the dipper is mounted, 95 said stick having a sliding and pivotal connection with the boom; mechanism for swinging the stick on the pivotal connection; mechanism for actuating the dipper stick in the sliding connection to effect a 100 sliding movement of the stick synchronously with the swinging movement; a motor actuating one of said mechanisms; means controlling said motor and controlled by the movement of the dipper stick under the influence of the other mechanism to automatically limit the dipper lip to a predetermined line involving a synchronous pivotal and 105 sliding movement of the dipper stick; and apparatus for varying and controlling the means to vary the line through which the dipper lip moves. 110

7. In a power shovel, the combination of a boom; a dipper having a cutting lip; a dipper stick on which the dipper is mounted, 115 said stick having a sliding and pivotal connection with the boom; mechanism for swinging the stick on the pivotal connection; mechanism for actuating the dipper stick in the sliding connection to effect a 120 sliding movement of the stick synchronously with the swinging movement; a motor actuating one of said mechanisms; means controlling said motor and controlled by the movement of the dipper stick under the influence of the other mechanism to automatically limit the dipper lip to a predetermined line involving a synchronous pivotal and 125

130

sliding movement of the dipper stick, said means being free for manual operation to move the dipper stick on one direction to control, the dipper stick at points above said line; and apparatus for varying and controlling the means to vary the line through which the dipper lip moves.

8. In a power shovel, the combination of a boom; a dipper having a cutting lip; a dipper stick on which the dipper is mounted, said stick having a sliding and pivotal connection with the boom; mechanism for swinging the stick on the pivotal connection; devices for actuating the dipper stick in the sliding connection to effect a sliding movement of the stick synchronously with the swinging movement; a motor actuating said devices; and means controlling said motor and controlled by the movement of said devices in swinging the dipper stick to automatically limit the dipper lip to a predetermined line involving a synchronous pivotal and sliding movement of the dipper stick.

25 9. In a power shovel, the combination of a boom; a dipper having a cutting lip; a dipper stick on which the dipper is mounted, said stick having a sliding and pivotal connection with the boom; mechanism for swinging the stick on the pivotal connection; devices for actuating the dipper stick in the sliding connection to effect a sliding movement of the stick synchronously with the swinging movement; a motor actuating said devices; means controlling said motor and controlled by the movement of said devices in swinging the dipper stick to automatically limit the dipper lip to a predetermined line involving a synchronous pivotal 30 and sliding movement of the dipper stick; and apparatus for varying and controlling the means to vary the line through which the dipper lip moves.

10. In a power shovel, the combination of a boom; a dipper having a cutting lip; a dipper stick on which the dipper is mounted, said stick having a sliding and pivotal connection with the boom; mechanism for swinging the stick on the pivotal connection; devices for actuating the dipper stick in the sliding connection to effect a sliding movement of the stick synchronously with the swinging movement; a motor actuating said devices; and means connected with the 45 dipper stick and controlling said motor by the swinging of the dipper stick to automatically limit the dipper lip to a predetermined line involving a synchronous pivotal and sliding movement of the dipper stick.

60 11. In a power shovel, the combination of a boom; a dipper having a cutting lip; a dipper stick on which the dipper is mounted, said stick having a sliding and pivotal connection with the boom; mechanism for swinging the stick on the pivotal connec-

tion; devices for actuating the dipper stick in the sliding connection to effect a sliding movement of the stick synchronously with the swinging movement; a motor actuating said devices; means controlling said motor; a link connection between said means and the dipper stick for automatically actuating said controlling means with a swinging movement of the dipper stick to carry the dipper lip to a predetermined line involving a synchronous pivotal and sliding movement of the dipper stick; and apparatus for varying and controlling the means to vary the line through which the dipper lip moves.

12. In a power shovel, the combination of a boom; a dipper having a cutting lip; a dipper stick on which the dipper is mounted, said stick having a sliding and pivotal connection with the boom; mechanism for swinging the stick on the pivotal connection; mechanism for actuating the dipper stick in the sliding connection to effect a sliding movement of the stick synchronously with the swinging movement; a motor actuating one of said mechanisms; and means controlling said motor comprising a cam actuated by the other of said mechanisms to automatically limit the action of the controlling means to carry the dipper lip to a predetermined line involving a synchronous pivotal and sliding movement of the dipper stick.

13. In a power shovel, the combination of a boom; a dipper having a cutting lip; a dipper stick on which the dipper is mounted, said stick having a sliding and pivotal connection with the boom; mechanism for swinging the stick on the pivotal connection; mechanism for actuating the dipper stick in the sliding connection to effect a sliding movement of the stick synchronously with the swinging movement; a motor actuating one of said mechanisms; means controlling said motor comprising a cam actuated by the other of said mechanisms to automatically limit the action of the controlling means to carry the dipper lip to a predetermined line involving a synchronous pivotal and sliding movement of the dipper stick; and apparatus for varying the relation between said means and said cam to vary the line through which the dipper moves under the control of said controlling mechanisms.

14. In a power shovel, the combination of a boom; a dipper having a cutting lip; a dipper stick on which the dipper is mounted, said stick having a sliding and pivotal connection with the boom; driving mechanism for swinging the stick on the pivotal connection; devices for actuating the dipper stick in the sliding connection to effect a sliding movement of the stick synchronously with the swinging movement; a motor for actuating said devices; a controlling mecha-

nism for the motor comprising a swinging lever; a hand lever for actuating the swinging lever; a link carried by the dipper stick; a rock arm connected to the link and actuated by the movement of the dipper stick through the link on the dipper stick; a cam lever pivoted on the rock lever; a connection between the cam lever and the link on the dipper stick; and a link extending from the controlling lever to the cam lever.

15. In a power shovel, the combination of a boom; a dipper having a cutting lip; a dipper stick on which the dipper is mounted, said stick having a sliding and pivotal connection with the boom; a driving mechanism for swinging the stick on the pivotal connection; devices for actuating the dipper stick in the sliding connection to effect a sliding movement of the stick synchronously 20 with the swinging movement; a motor for actuating said devices; a controlling mecha-

nism for the motor comprising a swinging lever; a hand lever for actuating the swinging lever; a link carried by the dipper stick; a rock arm connected to the link and actuated by the movement of the dipper stick through the link on the dipper stick; a cam lever pivoted on the rock lever; a connection between the cam lever and the link on the dipper stick; a link extending from the controlling lever to the cam lever; and means 25 for swinging the link between the controlling lever and the cam lever to vary the relation between the controlling mechanism 30 and the action of the dipper stick.

In testimony whereof I have hereunto set my hand in the presence of two subscribing witnesses.

EDWIN J. ARMSTRONG.
